IGNITION APPARATUS

John B. Dyer, Anderson, Ind., assignor to Delco-Remy Corporation, Anderson, Ind., a corporation of Delaware

Application December 11, 1931
Serial No. 580,277

5 Claims. (Cl. 123—117)

This invention relates to ignition apparatus for internal combustion engines.

One of its objects is to control the timing of the ignition in response to pressure in the engine 5 combustion chamber.

More particularly it is an object of the invention to retard the spark so as to prevent detonation and consequent loss of power while maintaining the greatest amount of spark advance 10 consistent with engine performance.

In order to accomplish this object the present invention provides cooperating cylinder and piston members, the former being connected to an engine cylinder and the latter to the interrupter 15 support of the ignition timer. Movement of the piston toward the right for retarding the spark is resisted by a spring which restrains movement of the piston from a spark advancing position to a spark retarding position until the pressure 20 in the combustion chamber of the engine rises substantially to the point of detonation. Thus when the detonation would tend to occur due to too great spark advance the spark is retarded so as to prevent the occurrence of detonation and 25 loss of power.

Further objects and advantages of the present invention will be apparent from the following description, reference being had to the accompanying drawing wherein a preferred embodiment 30 of one form of the present invention is clearly shown.

In the drawing:

The figure of the drawing is a diagram illustrating the present invention.

35 Referring to the drawing, the ignition apparatus comprises a coil 20 having a primary winding 21 and a secondary winding 22. The primary 21 is connected by a switch 23 with a battery 24 grounded at 25 and is connected by a wire 26 with a terminal 27 of an ignition timer. The terminal 27 is connected by a leaf spring conductor 28 with a circuit breaker lever 29 pivoted at 30 upon plate 31 which is rotatable about the axis of a shaft 32 which drives the ignition timer 40 cam 33. The cam 33 cooperates with a rubbing block 34 attached together with one end of the conductor 28, to the circuit breaker lever 29. Lever 29 carries a contact 35 cooperating with a grounded contact 36. The normal direction of 45 the rotation of the cam 33 is clockwise as indicated by arrow 37. Hence, to advance the spark the circuit breaker lever plate 31 is rotated counter-clockwise, and clockwise to retard the spark. 50

55 The means for controlling the angular relation

between the plate 31 and the cam 33 responsive to engine combustion pressures comprises a cylinder 40 extending from a timer housing 41 and cooperating with a piston 42 attached to a rod 43 passing through a threaded bushing 44 and attached by a pin 45 with a link 46 connected by pin 47 with the circuit breaker plate 31. A spring 48 is located between the piston 42 and the bushing 44 and is of such strength as to maintain the piston 42 substantially in the left-hand position shown in the figure until the engine cylinder pressure has increased substantially to a point where detonation would begin to occur. The cylinder 40 is connected by a pipe 49 with an engine cylinder or combustion chamber 50. 60 The left-hand wall of the cylinder 40 provides a seat 51 for a disc valve 52 having notches 53 at its periphery and a central bleed hole 54. A spring 55 located between the piston 42 and the valve 52 tends to retain the valve upon its seat. 65

Since the engine explosions occur intermittently the piston 42 is subjected intermittently to increases of pressure. As the pressure increases in the engine cylinder valve 52 opens to admit combustion products under pressure to 70 the left-hand end of the piston 42, thus tending to drive the piston toward the right. When the combustion pressure decreases in the engine cylinder, the valve 52 is closed by the spring 55. Since the bleed hole 54 in the valve 52 is relatively small, the pressure confined in the cylinder 40 is substantially retained during the period between explosions so that there is relatively little fluctuation of the piston 42. Hence the piston 42 tends to remain in the position to which it 75 was driven by a preceding explosion in the engine cylinder 50.

As the amount of work done in the engine cylinder increases the peak of the combustion pressure increases, thereby increasing the pressure 80 upon the piston 42 and still further compressing the spring 48. So long as detonation does not occur there will be relatively little compression of spring 48, but when there is a tendency for the explosive mixture to detonate, when exploding, the peak of detonation pressure is far in excess of the peak pressure before detonation occurs. The peak pressure of detonation although 85 of short duration, is transmitted to the piston 42 and overcomes the resistance offered by the spring 48 and drives the plate 31 a substantially angular distance in a clockwise direction. On account of the check valve 52 the piston 42 will 90 remain in a spark-retarding position at least until the next explosion takes place in the cylinder; 95

100

105

110

and that explosion will not detonate because the spark has been retarded. Then, since the spring 48 is not opposed by a detonating pressure the spring 48 will move the circuit breaker plate 31 to a more advanced position. In this way the spark timing is maintained advanced to the greatest degree consistent with proper engine performance but is promptly retarded so as to correct any tendency to detonate so that the engine will not be permitted to operate with loss of power and with a knocking or "pinging" sound.

While the form of embodiment of the present invention as herein disclosed, constitutes a preferred form, it is to be understood that other forms might be adopted, all coming within the scope of the claims which follow.

What is claimed is as follows:

1. Ignition apparatus for internal combustion engines comprising, in combination, a circuit interrupter for controlling an ignition coil, an engine driven cam for operating the interrupter, and means responsive to engine combustion chamber pressure for controlling the angular relation between the interrupter and cam, said means comprising a cylinder connected with an engine cylinder, a piston in said cylinder, a spring establishing an alterable predetermined spark advance relation between the interrupter and cam, and restraining movement of the piston from the spark advancing position to a spark retarding position until the engine cylinder pressure rises substantially to the point of detonation and means effective just after detonation tending to restore the predetermined spark advance relation, whereby the ignition will be timed to effect engine performance at combustion pressures below the detonating point.

2. Ignition apparatus for internal combustion engines comprising, in combination, a circuit interrupter for controlling an ignition coil, an engine driven cam for operating the interrupter, and means responsive to engine combustion chamber pressure for controlling the angular relation between the interrupter and cam, said means comprising a cylinder connected with an engine cylinder, a piston in said cylinder and a spring restraining movement of the piston from a spark advancing position to a spark retarding position until the engine cylinder pressure rises substantially to the point of detonation whereby the ignition will be timed to effect engine performance at combustion pressures below the detonating point; and means for damping movements of the piston due to intermittent application of pressures to the cylinder.

3. Ignition apparatus for internal combustion engines comprising, in combination, a circuit interrupter for controlling, an ignition coil, an

engine driven cam for operating the interrupter, and means responsive to engine combustion chamber pressure for controlling the angular relation between the interrupter and cam, said means comprising a cylinder connected with an engine cylinder, a piston in said cylinder and a spring restraining movement of the piston from a spark advancing position to a spark retarding position until the engine cylinder pressure rises substantially to the point of detonation whereby the ignition will be timed to effect engine performance at combustion pressures below the detonating point; and a check valve for controlling the passage between the control cylinder and engine cylinder, said check valve having a bleeder passage.

4. Ignition apparatus for internal combustion engines comprising, in combination, a circuit interrupter for controlling an ignition coil, an engine driven cam for operating the interrupter, and means responsive to engine combustion chamber pressure for controlling the angular relation between the interrupter and cam, said means comprising a cylinder connected with an engine cylinder, a piston in said cylinder and a spring restraining movement of the piston from a spark advancing position to a spark retarding position until the engine cylinder pressure rises substantially to the point of detonation whereby the ignition will be timed to effect engine performance at combustion pressures below the detonating point; and a check valve for controlling the passage between the control cylinder and engine cylinder, said valve including a valve disc having a bleeder passage, and a spring located between the control piston and valve disc for urging the disc against its seat.

5. Ignition apparatus for internal combustion engines comprising, in combination, a circuit interrupter for controlling an ignition coil, an engine driven cam for operating the interrupter, means responsive to engine combustion chamber pressure for controlling the angular relation between the interrupter and cam, said means comprising a pressure responsive element, means for communicating the pressure of the engine cylinder to said element, a spring restraining movement of said element from a spark advancing position to a spark retarding position until the engine cylinder pressure rises substantially to the point of detonation and means accelerating the return movement of said element from a spark retarding position toward a spark advancing position during the interval between successive detonations, whereby the ignition will be timed to effect engine performance at combustion pressures below the detonating point.
